DUTCH OVEN OR SIMILAR ARTICLE

David L. Painter, Evanston, Ill., assignor, by mesne assignments, to Rena-Ware Distributors Inc., Opportunity, Wash., a corporation of Washington

Application April 25, 1955, Serial No. 35,660

Term of patent 14 years

(Cl. D44—1)

FIG. 2

Fig. 1 is a top plan view of a Dutch oven or similar article embodying my new design;

Fig. 2 is a view in side elevation thereof; and

Fig. 3 is a cross-sectional view taken on the line 3—3 of Fig. 2.

I claim:

The ornamental design for a Dutch oven or similar article, substantially as shown.
